Elazar Thomas Perdue

UNITED STATES PATENT OFFICE.

ELEAZAR THOMAS PERDUE, OF HUGUENOT, VIRGINIA.

SOLAR-HEATING AUTOMATIC WELL-VENTILATOR.

SPECIFICATION forming part of Letters Patent No. 627,010, dated June 13, 1899.

Application filed December 29, 1897. Serial No. 664,299. (No model.)

To all whom it may concern:

Be it known that I, ELEAZAR THOMAS PERDUE, a citizen of the United States, residing at Huguenot, in the county of Powhatan and State of Virginia, have invented an improvement in Ventilating Wells, of which the following is a specification.

My invention relates to improvements in apparatus for ventilating wells, all of which will be fully described hereinafter, and particularly pointed out in the claims.

The object of my invention is to supply fresh air to a well by means of a pipe having one end extending above the well and exposed to the heat of the sun and the opposite open lower end stopping at a point above the water-line, whereby the outer projecting end of the pipe becomes heated, causing a rising of the air through the pipe and a consequent vacuum in the well, which is supplied with fresh air from above.

In the accompanying drawings, Figure 1 represents a well showing one form of my invention applied thereto. Fig. 2 is another sectional view of a well, showing a modified form of my invention applied thereto. Fig. 3 is a sectional view of a well, showing my device still further modified. Fig. 4 is a detached view of the lower end of the pipe within the well. Fig. 5 is a detached view of the hook for supporting the pipe. Fig. 6 is a detached view of the perforated cap at the outer end of the pipe.

Referring now to the drawings, in Figs. 1, 2, and 3 I show the dotted lines 1 and 2, indicating low and high water, and the lower end of the pipe should extend to a point above the water-line.

3 is a pipe which extends down within the well and has its lower end at a point above but adjacent the water-line and its upper end provided with a horizontal portion 4, which may be only a single portion of the pipe, as illustrated in Fig. 1, or formed into a number of coils, as shown in Figs. 2 and 3. The upper outer end of this pipe is turned upward, as shown at 5, and provided with a perforated cap 6 to prevent the admission of foreign matter into the pipe, while at the same time al-

lowing a free outward passage of the heated air from within the pipe.

Situated near the upper end of the well is a vertical standard 7, provided with a vertical series of perforations to receive a hook 5 for holding the horizontal portion of the pipe 4, and by means of which the pipe can be raised or lowered in the well to suit the height of the water.

It will be readily understood that that portion of the pipe which is exposed to the sun's rays will become heated and the air within the pipe consequently heated, causing an upward draft or current of air through the pipe, thus establishing to a certain degree a vacuum in the well above, but adjacent the water-line, which is supplied with fresh air, and this keeps the water sweet and healthy. It will also be readily understood that the larger amount of pipe exposed, like that illustrated in Fig. 3, will cause a greater amount of air to be withdrawn from the well than where a small amount of pipe is exposed to the rays of the sun, as illustrated in Fig. 1.

Having thus described my invention, what I claim, and desire to secure by Letters Patent, is—

1. An improved ventilating device for wells comprising a vertically-adjustable pipe extending down within the well and having open lower and upper ends, and a support for adjusting the pipe vertically, substantially as and for the purpose described.

2. An improved ventilating device for wells comprising a pipe extending vertically within the well and having an open lower end above but adjacent the water-line, the upper end of the pipe projecting outside of the well to be exposed to the heat of the sun, a vertical support outside of the well, and a vertically-adjusting supporting device carried by the vertical support for supporting the pipe in a vertical adjustment as and for the purpose described.

ELEAZAR THOMAS PERDUE.
